UNITED STATES PATENT OFFICE.

MARCO EVERARDO CALLEGARIS, OF MILAN, ITALY.

ORDINARY ELECTRIC WALL-SWITCH.

1,331,955.

Specification of Letters Patent. Patented Feb. 24, 1920.

Application filed March 8, 1919. Serial No. 281,497.

To all whom it may concern:

Be it known that I, MARCO EVERARDO CALLEGARIS, manufacturer, of Milan, Italy, Via Lulli 14, have invented certain new and useful Improvements in Ordinary Electric Wall-Switches, of which the following is a specification.

The invention relates to electric switches of the type generally used in connection with light-installations and fixed against walls. The invention has for its object a new construction of switches inexpensive to produce both from the point of view of material used and workmanship required.

With this end in view the switch comprises parts cut out of plates to suitable shape, and capable of being worked in a cold state, without the use of special tools.

In the annexed drawing one embodiment of the invention is shown.

Figure 1 is a cross section through the switch center-line,

Fig. 2 is an inverted plan view of same.

The switch comprises a body —1— of insulating material, formed with a cavity composed of three cylinders —16—17—18— of decreasing diameter.

The middle cylinder has diametrically opposed wall recesses —19—. —20— is a hole through the center of the body allowing passage of a spindle or equivalent, —2—, said spindle being formed from a plate folded on itself.

The upper end of said spindle is provided with a key —3— and the lower end is shaped into arms —4—.

On said arms seat the forked ends of a U-shaped member —5—, formed with a plate, said member forming an enlargement of the spindle and resting against blade-springs —6— mounted transversely of the upper cylinder cavity —18—. The springs 6 act as a detent to yieldingly hold the member 5 in either of its positions.

Between arms —4— and the bottom of cylinder cavity —17— are arranged the following members:

A metal disk —4'— on which seats coil spring —15—; a metal butterfly-plate —b— having a central square aperture in which the member 5 fits, said plate carrying wings —14— and resting on said spring, and an insulating disk plate —12—, carrying contact plates —a—, said plates on cross disk 12, being folded down at 7, and further being provided with extensions —9— lodged

in recesses —19—. Plate 12 has a central circular aperture of sufficient diameter to permit member 5 to rotate freely therein, while extensions 9 depending from said plate prevent any angular movement of said plate. The ends of said extension are pliable and constitute the terminals of the switch; the ends of the line-wire are coiled on said ends, and the latter are folded up to grip said wires, as shown in dotted lines in Fig. 1.

—8— is another insulating disk plate inserted between the bottom of cylinder cavity —19— and disk —12—.

All the members mentioned are pressed against the body by spring —15—.

The operation of the switch is as follows:

In the position shown the circuit between terminals —9— is closed through butterfly plate —b—.

Upon spindle —2— being turned through 90°, butterfly —b— will be rotated and the wings —14— brought on insulating disk —12— thereby opening the circuit.

The square section of member —5— resting between blade spring —6— is snapped at every quarter turn. Disks —12— and —8— have circular central holes, and do not take part in the rotation. Furthermore, disk —12— would be stopped in any movement caused by friction, by the plates —9— engaging in recesses —19—.

What I claim is:

1. A wall switch comprising a body formed with a plurality of cylindrical cavities with upwardly decreasing diameter, and a central hole; a spindle equivalent in said hole, with a key at one end and two arms at the other end, a forked member fitted on said spindle and seating on said arms, an insulating disk, a butterfly plate on said spindle with wings forming part of the butterfly plate sliding over said insulating disk, two contact plates on said disk, with projecting pliable terminals, and laminated springs to snap said forked member.

2. A wall switch comprising a body formed with a plurality of cylindrical cavities with upwardly decreasing diameter, and a central hole; a spindle equivalent in said hole, with a key at one end and two arms at the other end, a forked member fitted on said spindle and seating on said arms, an insulating disk, a butterfly plate on said spindle with wings forming part of the butterfly plate sliding over said insulating disk, a coil spring inserted between said spindle arms

- and said butterfly plate, two contact plates on said disk, with projecting pliable terminals, and laminated springs to snap said forked member.
- 5 3. A wall switch comprising a body formed with a plurality of cylindrical cavities with upwardly decreasing diameter, and a central hole; a spindle equivalent in said hole, with a key at one end and two arms at 10 the other end, a forked member fitted on said spindle and seating on said arms, a metal disk on said arms, an insulating disk, a butterfly plate on said spindle with wings form-

ing part of the butterfly plate sliding over the insulating disk, two contact plates on 15 said disk, with projecting pliable terminals, laminated springs to snap said forked member, and an insulating disk between said laminated springs and said contact-plates carrying disk.

20

In testimony whereof I affix my signature, in presence of two witnesses.

MARCO EVERARDO CALLEGARIS.
